HUMIDITY CONTROL FOR PRESSING MACHINES

Ernest Davis, Syracuse, N. Y., assignor to The Prosperity Company, Inc., Syracuse, N. Y., a corporation of New York

Application July 5, 1941, Serial No. 401,227

18 Claims. (Cl. 38—15)

This invention relates to machines, as garment and laundry pressing machines, where the fabric or articles are pressed while damp, and has for its object a particularly simple and economical means for automatically opening the press when the fabric or article has been dried to a predetermined dryness in order to prevent baking, scorching, etc. of the fabric or garment, which means is controlled by the amount of moisture expelled from the fabric or article by the heat of the pressing operation or by the conversion of the moisture into steam primarily under the movement of steam itself under its own expansion when passing or escaping through a confined outlet.

The invention further consists in a temperature responsive element exposed to a confined outlet passage for the steam generated by the heat of the pressing elements from the moisture in the fabric or article, while the steam is passing under its own natural pressure out of the chamber in one of the pressing elements into which it passes from the fabric or article, together with means for translating the motion or action of the temperature responsive element to a control member which effects the opening of the press when the garment is dried to a predetermined dryness.

It further has for its object a switch in an electric circuit having an electro-responsive device therein for operating and holding the control for the opening of the press, which switch is closed by the temperature responsive element under the action of the steam and opened in the absence of steam, or when the amount of steam generated from the moisture in the garment drops to a predetermined amount.

The invention consists in the novel features and in the combinations and constructions hereinafter set forth and claimed.

In describing this invention, reference is had to the accompanying drawings in which like characters designate corresponding parts in all the views.

Figure 1 is a diagrammatic view of this humidity control, the contiguous portions of the pressing element of the pressing machine, a portion of the actuating mechanism, and an operator control for the actuating mechanism and the release mechanism being also shown.

Figure 2 is a side elevation of a pressing machine embodying this invention.

Figure 3 is a front elevation, partly broken away.

Figure 4 is a fragmentary elevation of the up-

per and lower pressing elements with the upper element or head closed on the moist work-piece on the lower element and contiguous parts of the humidity control.

5 The invention is here shown as applied to a laundry pressing machine, in which the work is brought to the machine wet or damp. The pressing machine may be of any suitable form, size and construction and includes generally, 10 relatively movable, cooperative pressing elements having an opening and closing movement, and operator controlled actuating mechanism for effecting such movement.

The numeral 1 designates a lower pressing 15 element or buck suitably mounted on a frame 2 and 3 designates the movable pressing element or head having an opening and closing movement relatively to the buck 1. The head is carried by a head-carrying lever 4 pivoted between 20 its ends at 5 to an upstanding bracket or arm 6 on the frame. The actuating mechanism may also be of any suitable construction. That here illustrating includes generally, a pressure-operated motor, as a cylinder 7 having a piston 8 movable therein, the piston having its rod 9 connected through suitable motion transmitting mechanism at 10 to the rear arm of the head-carrying lever 4. The cylinder 7 is pivoted at 11 to the frame to have an oscillating movement.

30 The flow of motive fluid, as compressed air, to the cylinder is preferably controlled by a two-hand control, or a control requiring both hands of the operator. 12 and 13 designate, generally, the two hand controls. The control 12 includes 35 a two-way valve casing 14 and a combined intake and exhaust valve member 15 therein having a normally closed intake head 16 and a normally open exhaust head 17 connected together to act as a unit. A spring 18 normally holds the

40 valve intake head closed and the exhaust valve head open. The casing 14 is connected to a supply for compressed air through a pipe 19. The combined intake and exhaust valve is operated by a suitable manual, as a push button 20. 45 The other control 13 consists of a normally open, manually operated exhaust valve. 21 designates the exhaust valve casing; 22 the exhaust valve member or head operated to closed position by a push button 23. The casing 14 of the control 50 12 is connected by a pipe 24 to the intake port of the cylinder 7. The pipe 24 is connected by a pipe 25 to exhaust valve casing 21. Obviously, in order that air may pass to the cylinder, both push buttons 20 and 23 must be depressed. The motion of the push button 20 is transferred to

the valve member 15 through suitable spring retracted levers 28, 27 and likewise the motion of the push button 23 is transferred to the exhaust valve head 22 through levers 28, 29. The two hand control mechanism per se forms no part of this invention.

When the press is closed, the valves 15 and 22 are locked in their operated positions, as by pressure-operated motors, as diaphragms 30, 31 in diaphragm chambers 32, 33 associated with each of the valve casings 14, 21, the diaphragms acting through the levers 27, 29 to hold the valves in the casing 14 and 21 in their operated positions. The pressure sides of the diaphragm chambers are connected to a port 34 in the side wall of the cylinder 7 by a pipe 35 having branches 36, 37 leading to the pressure sides of the diaphragm chambers 32, 33. The port 34 is located to be passed by the piston 8 when the piston has passed far enough on the power stroke to bring the head 3 close to the buck 1. Ordinarily to open the press, a normally closed, manually operable release valve 38 is connected to the pipe 35 or one of the branches, as the branch 37 thereof. Hence when this release valve is opened, air is exhausted from the diaphragm chambers 32, 33 permitting the control valve members 15 and 22 to be returned to their normal positions by their springs, and hence permitting air to exhaust from the cylinder through the pipe 24 out through the combined intake and exhaust valve casing 14. The press then opens, usually under the action of counter-springs. In so far as this invention is concerned, the manual release is of no consequence. This invention relates to an automatic control performing the function of a release valve, the control being a valve, as the power is compressed air.

41 designates the automatic release, this, in the illustrated embodiment of the invention, being a valve including a casing having a normally open exhaust valve 42 therein, it being closed by a spring 43 and normally held open against the spring by means which is disabled by the steam generated from the moisture in the article being pressed and remains disabled until the article is dry when it is again operated to open the valve 42 against the spring 43 and effect the opening of the press.

The lower pressing element 1 on which the dampened garment is laid, is usually covered with a pervious or perforated cloth padding 44, while the pressing face of the head 3 is usually smooth or polished. The head 3 is also heated, it being usually formed with a steam heating chamber and also preferably the lower pressing element is steam heated. The steam for heating is supplied in any well-known manner. One of these elements, preferably the lower pressing element, is formed with a chamber 45 for receiving the steam generated from the moisture in the damp work when the press is closed, this being formed on the upper side thereof beneath the padding 44 and covered by a foraminous or perforated plate 46. A spring padding 47 is located between the cloth padding 44 and the plate 46. A wrapper 48 covers the padding 44. The assembly is such that when the press is closed, the only outlet for the steam generated from the moisture in the work, is into the chamber 45. The chamber 45 is also formed with an open outlet 49, this being shown as passing vertically through the buck 1 and opening at its upper end into the chamber 45. When the heated head 3 closes down onto the damp work W, it converts the moisture in the

damp garment into steam and the steam passes under its own pressure into the chamber 45 and out freely under its own pressure through the outlet 49 as long as there is any moisture in the garment to be converted into steam by the heat. The steam thus passes or moves under its natural pressure out of the chamber and the passage. The closing of the control valve 41 is effected by the action of the steam, and it is held closed as long as there is any steam or a predetermined minimum of steam passing through the outlet 49 under its natural pressure. When there ceases to be any steam or steam pressure, the outside air fills into the chamber through the outlet 49.

15 The means for controlling the closing of the automatic release valve 41 or the movable member 42 thereof, comprises a temperature responsive element 50 having a portion exposed to the outlet 49, this being mounted on a suitable bracket 51 on the support for the buck 1. The motion or warping action of the thermostatic element under the heating action of the steam is translated to the valve 41 to close it and hold it closed as long as there is a predetermined amount of steam or steam passing through the outlet 49. In the illustrated embodiment of the invention, the release valve 41 is opened against the action of its spring 43 by an electro-responsive device, solenoid or magnet 52, the core of which is connected to the valve head 42. The windings of the magnet 52 are connected in legs 53, 54 of an electric circuit having a switch 55 therein, the switch being normally closed and operated to open position by the action of the temperature

30 responsive element 50. As here shown, the switch is a tilting mercury switch. The switch is normally closed, and hence the valve head 42 open. When steam generated from the garment passes through the outlet 49, the switch opens, thus de-energizing the magnet 52 and permitting the control valve head 42 to close and hence hold the press closed. When under the heating action of the pressing elements, the garment or fabric is dried so that appreciably no steam is generated, the temperature responsive element reacts or cools causing the thermostat to close the switch 55 and the circuit through the magnet 52, and hence cause the magnet to open the control valve head 42, and permit the air to exhaust from the diaphragm chambers 32, 33 back through the pipes 31, 36 and pipe 56 which is connected to the pipe 36 out through the now open exhaust valve 41. The control valve 41 thus automatically performs the function of the manual release valve 38.

45 In order to keep the steam in motion through the outlet or keep it from lazing or lagging, a gentle injected jet of air commences to blow down through the outlet 49 immediately upon the closing of the press, through a pipe 57, this having a suitable regulating or needle valve 58 therein. The pipe 57 is connected to air pipe 24 controlled by the man-
uals 20, 23, the pipe terminating in an ejector nozzle 59 directed toward the discharge end of the outlet. Immediately upon the closing of the press, the air commences to blow to keep the steam in motion through the outlet 49 to the temperature responsive element. When the press is closed, the chamber 45 is air-tight against the inlet of air or outlet of steam between the pressing elements. The air nozzle thus keeps the steam in motion through the outlet, especially during the last of the drying operation when the steam and pressure are dying out.

70 In operation, after the damp garment has been

laid on the pressing element 1, the operator depresses both push buttons 20, 23 and when the press closes, the steam immediately generates. Usually on the first one or two closing operations, the operator holds the push buttons 20, 23 depressed a short interval after the press closes, until the thermostatic coil becomes warm. Thereafter, the operator merely holds the push buttons 20, 23 depressed until the press closes, as the steam generated from the moisture in the garment immediately becomes effective to heat the thermostat, de-energizing the magnet 52 to permit the exhaust valve head 42 to close under the action of its spring 43. When the moisture is extracted from the garment, so that little or no steam is being generated, the thermostatic coil cools or re-acts again closing the circuit to the magnet 52, causing the magnet to open the valve head 42 against the spring 43 and hence the exhaust of air from the cylinder 1 and the automatic opening of the press when the work-piece is dried.

What I claim is:

1. In a machine for pressing damp fabrics, the combination of relatively movable, cooperative pressing elements having a closing and opening movement, and actuating means for effecting such movement, at least one of said elements being heated, and one of said elements being formed with a chamber located to receive steam generated from the moisture in the garment by the heating action of the heated pressing element, the chamber having an outlet through which the steam passes under its own pressure only, and means operable by the steam passing through the outlet for holding the press closed and releasable to open the press by the absence of appreciable steam in the outlet due to the drying of said garment.

2. In a machine for pressing damp fabrics, the combination of relatively movable, cooperative pressing elements having a closing and opening movement, and actuating means for effecting such movement, at least one of said elements being heated, and one of said elements being formed with a chamber located to receive steam generated from the moisture in the garment by the heating action of the heated pressing element, the chamber having an outlet through which the steam passes under its own pressure, and means controlled by the steam in the chamber for holding the press closed and releasable to open the press by the absence of an appreciable amount of steam in the chamber, the last means including a temperature responsive element exposed to the steam in the outlet, a control for the holding means, and means operated by the temperature responsive element for operating the control to release the holding means when the steam generated from the moisture in the garment drops to a predetermined point.

3. In a machine for pressing damp fabrics, the combination of relatively movable, cooperative pressing elements having a closing and opening movement, and actuating means for effecting such movement, at least one of said elements being heated, and one of said elements being formed with a chamber located to receive steam generated from the moisture in the garment by the heating action of the heated pressing element, the chamber having an outlet through which the steam passes under its own pressure, means controlled by the steam in the outlet for holding the press closed and releasable to open

the press by the absence of steam in the outlet chamber, the last means including a temperature responsive element exposed to the steam in the outlet, a control for the holding means, means operated by the temperature responsive element for operating the control to release the holding means when the steam generated from the moisture in the garment drops to a predetermined point, and means for facilitating the passing of the steam through the outlet at least at the end of each steam generating operation.

4. In a machine for pressing damp fabrics, the combination of relatively movable, cooperative pressing elements having an opening and closing movement, at least one of said elements being heated, and one of said elements being formed with a chamber located to receive steam generated from the moisture in the damp garment by the heating action of the heated pressing element, mechanism for effecting the closing movement and releasable means for holding the press closed, a control for the holding means, and means operated by the flow of the steam from the chamber under its natural pressure only for holding the control member in its position assumed when holding the press closed, and releasable by the absence of steam in the chamber.

5. In a machine for pressing damp fabrics, the combination of relatively movable, cooperating pressing elements having an opening and closing movement, at least one of said elements being heated, and one of said elements being formed with a chamber in which steam is generated from the moisture in the damp garment by the heating action of the heated pressing element, mechanism for effecting the closing movement and releasable means for holding the press closed, a control member for releasing the holding means, means operated by the steam from the chamber for holding the control member in its position assumed when the press is closed, and releasable by the absence of steam in the chamber, the generator chamber having an outlet through which the steam passes under the pressure generated by the action of the heat on the moisture of the garment, the last means comprising a temperature responsive element extending into the outlet, and motion transmitting means operated thereby to hold the control member in holding position under the influence of the heat of the steam and to release the control when no steam is present in the generator chamber.

6. In a machine for pressing damp fabric, the combination of relatively movable, cooperative pressing elements having an opening and closing movement, actuating mechanism for effecting the opening and closing movement, and releasable means operable to hold the press closed, a control for the holding means normally in a position to hold the holding means in released position, at least one of said elements being heated, and one of said elements being formed with a chamber located to receive the steam generated from the moisture in the damp garment by the heating action of the heated pressing element, the chamber having an open outlet through which the steam passes under its own pressure, a temperature responsive element exposed to the action of the steam in the outlet, an electro-responsive device connected to the control to hold the control member in released position, a circuit therefor, a normally closed switch in the circuit, and connections operated by the temperature responsive element.

sive element under the action of the steam to open the switch when the steam is passing through the outlet and to close the switch in the absence of steam in the outlet and thereby effect the releasing operation of the control member to open the press when the fabric is dried.

7. In a machine for pressing damp fabric, the combination of relatively movable, cooperative pressing elements having an opening and closing movement, actuating mechanism for effecting the opening and closing movement, and releasable means operable to hold the press closed, a control for the holding means normally in a position to hold the holding means in released position, at least one of said elements being heated, and one of said elements being formed with a chamber located to receive the steam generated from the moisture in the damp garment by the heating action of the heated pressing element, the chamber having an open outlet through which the steam passes under its own pressure, a temperature responsive element exposed to the action of the steam in the outlet, an electro-responsive device connected to the control to hold the control member in released position, a circuit therefore, a normally closed switch in the circuit, and connections operated by the temperature responsive element under the action of the steam to open the switch when the steam is passing through the outlet and to close the switch in the absence of steam in the outlet and thereby effect the releasing operation of the control member to open the press when the fabric is dried, and means for facilitating the passing of the steam through the outlet at the end of each steam generating operation.

8. In a machine for pressing damp fabrics, the combination of relatively movable, cooperating pressing elements having an opening and closing movement, at least one of said elements being heated, and one of said elements being formed with a chamber in which steam is generated from the moisture in the damp garment by the heating action of the heated pressing element, mechanism for effecting the closing movement and releasable means for holding the press closed, a member for releasing the holding means, means operated by the steam from the chamber for holding the control member in its position assumed when the press is closed, and releasable by the absence of steam in the chamber, the chamber having an outlet through which the steam passes under the pressure generated by the action of the heat on the moisture of the garment, the last means comprising a temperature responsive element extending into the outlet, and motion transmitting means operated thereby to hold the control member in holding position under the influence of the heat of the steam and to release the control when no steam is present in the generator chamber, and means rendered operative by the closing of the press to facilitate the movement of the steam through the outlet.

9. In a machine for pressing damp fabrics, the combination of relatively movable, cooperating pressing elements having an opening and closing movement, at least one of said elements being heated, and one of said elements being formed with a chamber in which steam is generated from the moisture in the damp garment by the heating action of the heated pressing element, mechanism for effecting the closing movement and releasable means for holding the press closed, a member for releasing the holding means, means operated by the steam from the chamber for holding the control member in its position assumed when the press is closed, and releasable by the absence of steam in the chamber, the chamber having an outlet through which the steam passes under the pressure generated by the action of the heat on the moisture of the garment, the last means comprising a temperature responsive element extending into the outlet, motion transmitting means operated thereby to hold the control member in holding position under the influence of the heat of the steam and to release the control when no steam is present in the generator chamber, an air conduit having a nozzle in the outlet directed toward the discharge end of the outlet, and means operated by the closing movement of the press to control the flow of air through the conduit when the press is closed.
10. In a machine for pressing damp fabric, the combination of relatively movable, cooperative pressing elements having an opening and closing movement, actuating mechanism for effecting the opening and closing movement, and releasable means operable to hold the press closed, a control for the holding means normally in a position to hold the holding means in released position, at least one of said elements being heated, and one of said elements being formed with a chamber located to receive the steam generated from the moisture in the damp garment by the heating action of the heated pressing element, the chamber having an open outlet through which the steam passes under its own pressure, a temperature responsive element exposed to the action of the steam in the outlet, an electro-responsive device connected to the control to hold the control member in released position, a circuit therefore, a normally closed switch in the circuit, and connections operated by the temperature responsive element under the action of the steam to open the switch when the steam is passing through the outlet and to close the switch in the absence of steam in the outlet and thereby effect the releasing operation of the control member to open the press when the fabric is dried, and means for effecting a quick cooling of the temperature responsive element and facilitating the movement of the steam through the outlet, the last means being controlled and made operative by the closing movement of the press.

ERNEST DAVIS.

CERTIFICATE OF CORRECTION.

Patent No. 2,296,910.

September 29, 1942.

ERNEST DAVIS.

It is hereby certified that error appears in the printed specification of the above numbered patent requiring correction as follows: Page 2, second column, line 46, for "thermostat" read --temperature responsive element--; and that the said Letters Patent should be read with this correction therein that the same may conform to the record of the case in the Patent Office.

Signed and sealed this 24th day of November, A. D. 1942.
